SPECTACLE FRAME OR THE LIKE

Walter C. Carmichael, Lexington, Mass., assignor
to American Optical Company, Southbridge,
Mass., a voluntary association of Massachusetts

Application June 16, 1953, Serial No. 25,516

Term of patent 14 years

(Cl. D57—1)

To all whom it may concern:

Be it known that I, Walter C. Carmichael, a citizen of the United States of America, residing at Lexington, in the county of Middlesex and State of Massachusetts, have invented a new, original, and ornamental design for a Spectacle Frame or the like, of which the following is a specification, reference being made to the accompanying drawing, forming a part thereof.

Fig. 1 is a front elevational view of a spectacle frame showing my new design;

Fig. 2 is a top plan view of the spectacle frame shown in Fig. 1, with the ends of the temples broken away; and

Fig. 3 is a perspective view thereof.

The characteristic features of my new design are shown in full lines in the drawing.

I claim:

The ornamental design for a spectacle frame or the like, substantially as shown and described.

WALTER C. CARMICHAEL.
